UNITED STATES PATENT OFFICE.

JAMES G. GRACEY, OF ST. LOUIS, MISSOURI.

HYDRAULIC-CYLINDER LUBRICATOR.

SPECIFICATION forming part of Letters Patent No. 416,598, dated December 3, 1889.

Application filed April 3, 1889. Serial No. 305,884. (No model.)

To all whom it may concern:

Be it known that I, JAMES G. GRACEY, of St. Louis, Missouri, have made a new and useful Improvement in Hydraulic-Cylinder Lubricators, of which the following is a full, clear, and exact description.

The improvement relates to that class of hydraulic-cylinder lubricators in which the lubricant is applied to a holder which travels with the piston and piston-rod in the movement thereof to and fro in the cylinder, and in its movement transfers the lubricant to the cylinder-shell, and has for its object an improved means for adjusting the lubricant-holder and keeping it in contact with the inner surface of the cylinder, substantially as hereinafter described and claimed, aided by the annexed drawings, making part of this specification, and of which—

Figure 1 is a cross-section of a hydraulic cylinder having the improved lubricator in position; and Fig. 2, a vertical longitudinal section on the line 2 2, Fig. 1, looking to the right, as there shown.

The same letters of reference denote the same parts.

A represents the improved lubricator in position in a hydraulic cylinder B; C, the piston-rod, which is clasped by the clamp composed of the two parts D D', which are pressed together by the screw-bolts d d'. The part D of the clamp is provided with a projecting arm d², which is threaded at its upper end and provided with the two nuts d³ and d⁴, which serve to hold in place between them the lug F, the extremities whereof are firmly attached by the bolts e e to the lubricator-holder frame E, which is a metal spring-bow the upper and central portion whereof is pressed upward and outward by the said lug F. The two lower and end portions of the frame E are pressed outwardly by the curved expansion-braces G G', the outer ends whereof are firmly attached, respectively, to the ends of the said frame by the screw-bolts e' e'. The inner ends of the braces G G' are adapted to apply, respectively, to the outer edges of the two wedge-shaped parts d⁵ d⁶ of the clamp parts D D', as shown, and are each provided with a longitudinal slot g, Fig. 2, for receiving the screw-bolt d', by which, together with the nut and beveled washers thereof, the said

inner ends of the braces G G' are held in place against the said outer edges of the wedge-shaped parts d⁵ d⁶.

Any suitable material of an elastic spongy nature, capable of absorbing, holding, and distributing the lubricant, may be employed as a lubricant-holder, and it may be attached in any suitable manner to the lubricant-holder frame E; but I consider as desirable the lubricant-holder and the means of attaching it to the holder-frame shown, and of which the following is a description: The outer surface of the frame E is first covered with leather e², which in turn is covered with tanned sheep-skin e³ with the wool on—which is, say, about two and a half to three inches thick—and both of said layers are riveted to the frame E by a sufficient number of rivets e⁴, extending through the sheep-skin, leather, and frame.

The operation of the improvement is as follows: The lubricant is fed to the lubricant-holder (which in the present instance is the wool) in any suitable manner. By means of the proper adjustment of the nuts d³ and d⁴ on the projecting arm d² the lug F is caused to press upwardly against the frame E, and thereby produce the desired pressure of the upper and central portion of the lubricant-holder against the cylinder-surface. The desired pressure of the lower and end portions of the lubricant-holder against the cylinder-surface is obtained by properly shaping the expanding braces G G', so as to produce said desired pressure when the outer ends of the braces are firmly attached to the end portions of the lubricant-holder, as shown, and the inner ends of the braces are attached to the edges of the wedge-shaped parts d⁵ d⁶ after being placed so that the bolt d' rests against the upper ends of the slots in said braces.

By continued use the spongy lubricant-holder naturally becomes more or less compressed, and thereby fails to touch or to press against with sufficient force the cylinder-surface. To easily remedy the above-described condition is the main object of this improvement, and it is effected in the following manner: Slack up the nut on the bolt d' so as to allow the ends of the braces to slide freely up and down the length of the slots therein. By means of the nuts d³ and d⁴ on the projecting

arm d^2 raise the lug, and thereby the frame and holder until a desired pressure of the central part of the holder against the cylinder-surface is again obtained. When the upper 5 part of the frame and holder are thus raised, the lower parts thereof are of course also raised, and with them also the expansion-braces G G' throughout the length thereof, as they are firmly attached to the holder-frame 10 by the bolts e' e'. When the said braces rise, the inner ends thereof, which press against the wedge-shaped parts d^5 d^5 , are thereby spread farther apart, and are thus caused to press the lower end portion of the holder 15 against the cylinder-surface. This pressure of the lower parts of the holder against the cylinder-surface can then, or at any other time, be regulated and set, as desired, with exactness, independently of the upper parts, 20 by the proper manipulation and adjustment of the inner ends of the braces G G'. The outward pressure of the lower parts of the holder is increased by sliding the inner ends

of the braces upwardly, and decreased by a reverse movement.

The herein-described improvement may be attached to the piston of the cylinder instead of to the piston-rod thereof without departing from the essence of my invention.

I claim—

1. A hydraulic-cylinder lubricator having the lubricant-holder attached to a spring-bow, which in turn is supported from the piston-rod, substantially as described.

2. The combination of the lubricant-holder 35 e^3 , the spring-bow E, the piston-rod C, the clamp D D', having the wedge-shaped parts d^5 d^5 , and the projecting arm d^2 , the lug F, and the braces G G', substantially as and for the purpose described.

Witness my hand March 27, 1889.

JAMES G. GRACEY.
